ESCUOTCHEON PLATE WITH PUSHBUTTON FOR DOORBELLS

Lawrence P. Mellyn, Gloucester, R.I., assignor to
General Electric Company

Filed Mar. 27, 1972, Ser. No. 238,746

Term of patent 14 years

Int. Cl. D8—09

U.S. Cl. D8—181

FIG. 1 is a perspective view of an escutcheon plate with pushbutton for doorbells embodying my new design;
FIG. 2 is a front elevational view thereof;
FIG. 3 is a side elevational view thereof;
FIG. 4 is a back elevational view thereof;
FIG. 5 is a side elevational view of the other side thereof;
FIG. 6 is a top plan view thereof;
FIG. 7 is a bottom plan view thereof.
I claim:
The ornamental design for an escutcheon plate with pushbutton for doorbells, as shown.
